UNITED STATES PATENT OFFICE.

EDWARD A. MELLINGER, OF CHICAGO, ILLINOIS, ASSIGNOR, BY MESNE ASSIGNMENTS,
TO AUTOMATIC ELECTRIC COMPANY, A CORPORATION OF ILLINOIS.

TELEPHONE SYSTEM AND APPARATUS.

1,317,522.

Specification of Letters Patent. Patented Sept. 30, 1919.

Application filed April 3, 1906. Serial No. 309,637.

To all whom it may concern:

Be it known that I, EDWARD A. MELLINGER, a citizen of the United States of America, and resident of Chicago, Cook county, Illinois, have invented a certain new and useful Improvement in Telephone Systems and Apparatus, of which the following is a specification.

My invention contemplates certain improvements on the subscriber's individual trunk-selecting and connecting apparatus of an automatic or semi-automatic telephone exchange system.

Generally stated, the object of my invention is the provision of an improved and highly efficient system of apparatus for enabling a calling telephone subscriber to automatically select and obtain connection with an idle trunk-line or other trunking connection before any switching or connecting operations are performed in accordance with the number of the called subscriber; for, obviously, an automatic trunk-selecting apparatus of this particular character can be employed in exchanges where either automatic or manual switchboards are used for completing the connections in accordance with the number of the called subscriber.

Special objects of my invention are the provision of an improved construction and arrangement whereby the individual-switches of the subscribers' lines are initially actuated to close connection with a pre-selected trunk-line, by the mere closing together of the two sides of the calling subscriber's line, which line is, of course, normally open at the sub-station; the provision of an improved construction and arrangement whereby the connection with a pre-selected trunk-line is obtained positively by the energizing of a magnet in the calling subscriber's individual-switch, the plunger which responds to the pull of the energized magnet being held in its normal position by a spring; the provision of an improved construction and arrangement whereby the plungers of any individual-switches in use are positively locked in position to temporarily maintain the desired connections between the calling subscribers' lines and the trunk-lines leading to the switching apparatus for completing connections in accordance with the called number; and the provision of certain details and features of improvement and novel combinations tending to in-

crease the general efficiency and serviceability of subscribers' individual trunking switches of this particular character.

To the foregoing and other useful ends, my invention consists in matters hereinafter set forth and claimed.

In the accompanying drawings, Figure 1 is a diagrammatic illustration of my improved individual-switch A which is operated the instant that the subscriber to whom said switch is allotted removes his receiver from the switch-hook, preparatory to making a call, by current from the central or common battery B, the master-switch C allotted to said individual-switch being shown directly beneath.

Fig. 2 is a similar view and shows the plunger-arm of the individual-switch A in an operated position.

Fig. 3, in a similar manner, shows a calling subscriber #50 and a called subscriber #20 connected through the individual-switch A, a connector D, and a called individual-switch A¹.

Fig. 4 is a diagrammatic perspective view showing the connector-switch in detail.

The sub-station may be of any suitable, known or approved type. Said sub-station has the well-known impulse-wheel 2 provided with the usual vertical impulse-teeth 3 which are adapted to operate the vertical impulse-spring 4 in such manner that the said spring may be pressed intermittently against the ground-post 5 for the purpose of sending ground impulses to the vertical-line-conductor of the subscriber's line. Furthermore, the said impulse-wheel has a rotary impulse-tooth 6, which, after the vertical impulses are sent, acts upon the rotary impulse-spring 7 so that one ground impulse is sent to the rotary-line-conductor of the subscriber's line. The switch-hook 8 will be recognized, also the cam-arms 9, 10 and 11 thereof. The cam-arm 11 controls the so-called locking-cam 12, so that when the switch-hook rises, and before the dial is rotated, the insulating tip 13 upon the end of said locking-cam is driven to the inner edge of the angled section upon the end of the so-called ground-spring 14, whereby when the dial (which is not shown) is pulled down by the calling subscriber the pin 15 upon the end of the locking-dog 16 raises the said locking-cam 12 a trifle more and causes the said insulating tip 13 to fall behind the said angled sec-

tion upon the ground-spring 14 and permits the latter to make electric contact with a second ground-spring 17. The engagement of the said ground-springs 14 and 17, after the operation described, places the ground-post 5 in connection with ground, whereby when the subscriber releases the dial, after having pulled it down as described, the vertical impulse-teeth 3 will act first upon the vertical impulse-spring 4, and after that the rotary impulse-tooth 6 acts upon the rotary impulse-spring 7, as described. The subscriber is, of course, provided with a transmitter 18 and induction-coil 19, the primary winding 20 of which is connected normally, when the switch-hook is raised, in series with said transmitter 18 and with the subscriber's line; and the secondary winding 21 connected in a local closed circuit in series with the receiver 22. Furthermore, the sub-station is provided with a ringer 23 in series with a condenser 24, which ringer and condenser, when the switch-hook is down, are connected in series across the subscriber's line. When the switch-hook is down the cam 10 maintains the switch-springs 25 and 26 in contact, whereby the said ringer and condenser are maintained across the line; but the spring 25 being depressed, two other switch-springs 27 and 28 are kept normally separated, which, when the switch-hook rises, are closed while the first pair of springs 25 and 26 spring apart. It will be noticed that the said springs 27 and 28 control the connection between the two conductors of the subscriber's line, through the aforesaid transmitter 18 and primary winding 20 of the induction-coil 19. Even after the switch-hook is raised, since the finger 29 upon the cam-dog 16 controls the position of the spring 28, and since the said cam-dog rotates in unison with the dial, and as long as the said dial is out of normal position, the springs 27 and 28 and, therefore, the subscribers' line-conductors are kept separated for the time. The signaling device whereby a subscriber may signal a called subscriber, after he has established connection, comprises a push-button 30 and a spring 31 which normally engages a contact-point 32; but when the push-button 30 is pressed the spring 31 leaves the contact 32 and passes into engagement with the contact-point 33 which is at that time connected with ground. The means whereby a subscriber may release the central office switching apparatus, after said apparatus is once disturbed, comprises three release-springs 34, 35 and 36 so controlled by the cam-arm 9 that when the switch-hook descends the said springs are pressed into contact, whereby both sides of the subscriber's line are grounded simultaneously.

The individual-switch A, as shown in Fig. 1, connected to the subscriber's line

#50, like all other individual-switches employed in my improved system, is built about a suitable frame 37 which comprises two electromagnets 38 and 39, the former known as the actuating or trip-magnet and the latter as the release-magnet. Between the said magnets there is an upright 40 that supports the plunger-arm 41, upon the end of which latter the plunger 42 is suitably pivoted by the pin 43. Normally the said plunger-arm 41 is retained away from the pole-piece of the trip-magnet 38 by the retracting-spring 44, whereby the plunger 42 is retained in normal engagement with the plunger-shaft 45. Said plunger-shaft is controlled by the common master-switch C and to one end of said shaft the master-switch-cam 46, as well as the wiper 47, are rigidly secured. The said plunger-shaft 45 is provided with a longitudinal groove or trough into which the butt 48 of the plunger 42 snugly fits so that whenever the said shaft 45 is rotated all plungers that may be in engagement with said shaft are caused to travel with the latter. Attached to the said plunger-arm 41 is an armature 49 which is attracted by the magnet 38 whenever the latter is energized. Said magnet 38 is in addition provided with a second armature 50 that is pivoted at one end to the frame 37. The said armature 50 has an arm 51 that controls a couple of springs 52 and 53 for purposes which shall hereinafter be described. The said springs are also controlled by a member 54 upon the plunger-arm 41 in such a manner that when the said arm is attracted the springs 52 and 53 may be separated. The magnet 39 has a similar armature 55 that controls the springs 56 and 57 with respect to the springs 58 and 59, so that when the said armature 55 is attracted the said springs 56 and 57 are separated, respectively, from the springs 58 and 59. The plunger-arm 41 may be locked either in its normal or in its operative position by the said armature 55. If the magnet 39 were energized when the armature 41 is in normal position the rear end 60 of said armature is caught in the angled section 61 of said armature, whereby the plunger-arm 41 is prevented from carrying the plunger 42 into engagement with the individual-switch-bank E, if the magnet 38 is energized at such a time. Again, if the armature 55 is attracted after the plunger 42 is lodged in the bank E, the chamfered end 60 of the arm 41 is then engaged by the angled terminal 62 of the armature 55 whereby it is impossible after such engagement for the arm 41 to return to normal position until the magnet 39 is deenergized. The different locked positions of the said arm 41 are clearly shown in Fig. 2. In connection with the master-switch C, as more clearly shown in Fig. 3, there is an auxiliary-relay 63

which controls a couple of springs 64 and 65 that are, when the said relay 63 is energized, closed in contact, and a signal-lamp 66 is lighted to indicate that a subscriber's 5 line of a group is troubled with a grounded line. The bank E allotted to the individual-switch A is composed of ten sets of springs similar to the springs 67, 68, 69, 70, 71 and 72, all of which are normally disengaged, 10 but whenever the plunger-arm 41 is attracted by the magnet 38 the plunger 42 that carries a wedge-like insulation cam 73 is thrust into one of said bank positions, and into engagement with one of said sets 15 of springs, whereby the springs 68, 69 and 70, for example, are thrust into engagement with the corresponding springs 67, 72 and 71. Each spring in each bank is properly insulated from all other springs, and since 20 there are ten sets to each bank there will be ten springs like the spring 67, ten like the spring 68, and so on. However, the ten springs of each bank (similar to the spring 68) are all connected in multiple, as well as 25 all the springs similar to the spring 69—and also all of the springs similar to the spring 70—but all of said multiple springs are separated from each other. It will be understood, of course, that in a way well-known to those skilled in the art all corresponding springs, or sets of springs, in each bank are connected in multiple to all corresponding springs or sets of springs in all other banks of the same group. Each bank 30 forms a unit and the parts are all suitably held together by means of clamping-plates or other devices if desired. Of the springs of the bank E, the springs 72 and 71 constitute the terminals of one of the trunk-lines 35 that terminate in the said bank, while the spring 68 constitutes the terminal of the so-called third release-trunk, which trunk includes the relay 74. For each trunk-line there is provided a relay similar to said 40 relay 74, and in a decimal system of that order ten trunk-lines for each set of one hundred subscribers to each of such group there will be allotted, of course, ten such 45 relays.

50 The master-switch C is of a well-known type. To the said switch there is allotted a bank comprising ten or a suitable number of bank-contacts *a* and a common metallic plate 75. The wiper 47 is designed to engage 55 the said contacts *a* one at a time and to thereby connect the particular contact *a* engaged with the common plate 75. The movement of the wiper 47 is accomplished through the medium of the ratchet-wheel 60 76 that is provided with a number of pins 77, 78, 79 and 80 with which the cam 46 operates, engaging one of said pins one at a time in a well-known manner. Said ratchet-wheel is operated by ratchet and pawl 65 mechanism, which pawl 81 is carried by the interrupter-arm 82 of the motor-magnet 83. Said magnet 83 is in a normally open circuit including the interrupter-springs 84 and 85 and the relay-springs 86 and 87. When said magnet 83 is energized the armature 82 is 70 attracted and the circuit interrupted at the springs 84 and 85; but the interruption does not occur until the end of the attractive stroke of said armature, in any suitable manner well-known to those skilled in the 75 art. By means of said ratchet and pawl mechanism the wiper 47 is advanced one step at a time for purposes to be hereinafter described. The circuit controlling relay 88 of the master-switch C that controls the energizing 80 circuit of the motor-magnet 83, through the medium of the springs 86 and 87, is connected in series with an auxiliary-relay 89 which, through the medium of the springs 90 and 91, controls the energizing 85 circuit for the trip-magnet 38. It will be clear that backward rotation of the ratchet-wheel 76 is checked by the pawl 92 and that each step given to the said ratchet-wheel is made positive and definite by the guide-post 93. As is well understood, each of the contact-points *a* is allotted to one of the trunk-lines leading from the individual-switch-banks; and each time one of said trunks is occupied by some individual-switch 90 the corresponding one of said bank-contacts *a* of the master-switch is supplied with a guarding potential to prevent the wiper 47 from stopping upon such a contact when it is busy. The trunk-line shown terminating 100 in the springs 72 and 71, for instance, is allotted a contact-point 94, and the guarding potential to that contact-point is established whenever the relay 74 is energized, at which time the springs 95 and 96 are forced into 105 contact, and the said contact-point 94 is placed in communication with the non-grounded terminal of battery B. The method of operation of the individual-switch A and of the circuits controlled by 110 said switch, will be described.

As already stated, the connector-switch D, shown in Figs. 3 and 4, may be of any suitable, known or approved type, and I have elected to describe my invention in connection 115 with the connector-switch herein shown. Said connector is of the general type described in Patent No. 815,176 granted March 13, 1906, the circuits being changed with reference to common battery work. Said 120 connector is, therefore, of the common battery type, and is provided with the usual switch-shaft 97 by means of which the line-wipers 98 and 99 and the private-wiper 100 are raised to any one of ten levels and rotated onto any one of ten sets of bank-contacts. Said line-wipers are adapted to engage the line-bank 101 and the private-wiper 100 is adapted to engage the private-bank 102. The said switch-shaft carries, as usual, 125 130

a cam 103 and a set of longitudinal teeth 104 and a set of circular teeth 105, which latter are traversed by a longitudinal slot 106 into which the end of the shaft-rest 107 normally projects. Furthermore, the said switch-shaft carries the well-known normal-post-arm 108 that controls the switch-shaft-springs 109 and 110. Said shaft is retained in normal position, with the normal-post-arm 108 against the normal-post 111, by the coil-spring 112, which latter has the inner end thereof secured to the said switch-shaft, and the other end to the normal-post 111. The operative magnets—that is, the vertical-magnet 113, the rotary-magnet 114, the release-magnet 115, as well as the private-magnet 116 and ringer-relay 117—are controlled by means of the vertical and rotary line-relays 118 and 119, respectively. The said connector is provided with a differential-relay 120 for releasing purposes, and with a double-wound back-bridge-relay 121 that controls the supply of talking current to the calling subscriber. The vertical-line-relay when energized is adapted to press the line-relay-spring 122 onto the ground-spring 123 and the trunk-release-spring 124 in the direction of the second trunk-release-spring 125. The rotary-line-relay 119 in turn, when energized, presses the line-relay-spring 126 onto the said ground-spring 123 and allows the trunk-release-spring 125 to flex in the direction of the aforesaid trunk-release-spring 124. The adjustment is such that when both of the line-relays 118 and 119 are energized simultaneously the trunk-release-springs 124 and 125 come into contact for releasing the switches, as will be described. The private-magnet 116 controls the private-springs 127, 128, 129 and 130 as usual, and the former two of said springs (127 and 128) are normally in contact while the springs 129 and 130 are normally out of contact. When the private-magnet is energized, however, the last two of said springs close in engagement and the first two flex apart. The ringer-relay 117 is given control over the ringer-relay-springs 131 and 132, whereby the spring 131, when the said ringer-relay is energized, is separated from the spring 133 and pressed onto the spring 134, and at the same time the spring 132 is pressed onto the spring 135. This operation of the ringer-relay places the ringer-generator 136 across the called subscriber's line, thus ringing the said called subscriber over circuits to be described. As is well-known, when the vertical-magnet 113 is energized the first time the so-called release-link 137 that normally locks the double-dog 138 in normal position is withdrawn from engagement with said double-dog, so that the latter by force of the retracting-spring 139 is rotated about the pivots 140, at which time the vertical-dog

141 is placed in working engagement with the circular teeth 105, and the rotary-dog 142 is placed in working engagement with the longitudinal teeth 104. The double-dog 138 being thus released the vertical-dog 141 supports the shaft 97 at whatever position the vertical-magnet 113, by means of the vertical-pawl 143, may raise the shaft 97. And likewise, after being raised, the rotary-dog 142 retains the shaft in whatever rotary position the said shaft 97 may be rotated by the rotary-magnet 114 through the medium of the rotary-pawl 144. The release-magnet 115, whenever energized, attracts its armature 145, which latter with the elongated portion 146 strikes the double-dog 138 to the right of the bearings 140 and deprives the shaft of its support, at the same time restoring the well-known side-switch F to normal position, moving it about the pivots 147 through the medium of the arm 148 and the side-switch-link 149. Said side-switch, as usual, comprises a number of side-switch-wipers 150, 151, 152 and 153 which are adapted to be switched into any one of three positions. In the first position the said wipers are retained in engagement with the contact-points 154, 155, 156 and 157; and in the second position in engagement with the contact-points 155^a, 156^a, 157^a and 158; and in the third position in engagement with the contact-points 159, 160, 161 and 162. The side-switch-arm 163 is provided at its right extremity with the so-called escapement-finger 164, which latter is controlled by the escapement device upon the armature 165 of the private-magnet 116. Said escapement device comprises four teeth 166, 167, 168 and 169, the first two teeth and the last two teeth being slightly out of alignment. The said escapement is designed to reduce the outward movements of the connector-side-switch to a step-by-step operation under the retracting tension of the spring 170. When the side-switch is in first position the escapement-finger 164 is retained behind the tooth 168, when in second position behind the tooth 169, and when in the third position in engagement with the side-switch-stop 171. The differential-relay 120 is given control of three springs 172, 173 and 174, so that when the said relay is energized the spring 173 that normally engages the spring 172 is withdrawn therefrom and pressed instead in engagement with the spring 174. Similarly, the double-wound relay 121 controls three springs 175, 176^a and 177^a. Said relay when energized forces the spring 176^a that normally engages the spring 175 away from said spring and into engagement instead with the spring 177^a.

When the subscriber at the sub-station #50, in calling sub-station #20, removes his receiver 22 from the switch-hook 8, as previously described, he causes the springs 27

and 28 to come into contact and the springs 25 and 26 to separate. This follows from the fact that the cam-arm 10 leaves the spring 25. The closure of said springs establishes an energizing circuit for the trip-magnet 38. It will be assumed that the set of springs of the bank E, shown in Fig. 1, is the first set of springs in said bank, and, of course, at such a time, the wiper 47 of the master-switch will be in engagement with the contact-point 94, maintaining the said contact with the common plate 75. The current that energizes the said trip-magnet 38, at the removal of the receiver, comes from ground G1 at the master-switch C through the springs 91 and 90, and through the said trip-magnet 38, springs 59 and 57, rotary-line-conductor 176, primary winding 20, and transmitter 18 to the vertical-line-conductor 177, thence through the springs 56 and 58 and through the auxiliary-relay 63 to the battery-lead 178, to the non-grounded terminal of battery B and to ground G. The said magnet 38 becoming magnetized attracts both armatures 49 and 50, the former against the tension of the retracting-spring 44 and the latter against the tension of the spring 53. The tension of the last said spring is so slight that the armature 50 responds very quickly and ahead of the armature 49. Therefore, the springs 52 and 53 are brought into contact by the arm 51 when the armature 50 is attracted. As a result the auxiliary-relay 63 and the line-conductors 176 and 177, together with the primary winding 20 and transmitter 18, are shunted out of the energizing circuit for the magnet 38. The energizing circuit in this last case for the said magnet 38 extends from ground G¹ through the said magnet and through the springs 52 and 53 to the non-grounded terminal of battery B to ground G. At once the magnetizing power in the magnet 38 is increased to a great extent, and the armature 49 responds by driving the plunger 42 between the springs 68 and 69, so that the said springs are respectively pressed into engagement with the springs 67 and 72 and at the same time the spring 70 is forced onto the spring 71. It will be noticed that the great advantage presented by the use of the springs 52 and 53 is that if the line-conductors 176 and 177 are long and the resistance out on the line is great the magnet 38 will not receive enough power to attract the armature 49 against the tension of the retracting-spring 44. Therefore, I provide means whereby the action of the plunger-arm 41 becomes positive irrespective of the resistance of the outside lines and circuits. By the time that the plunger 42 is driven home in the bank E the armature 49 strikes the pole of the magnet 38, as shown in Fig. 2, and the member 54 then separates the springs 52 and 53 and restores the original circuit to the said magnet 38 through the transmitter at the sub-station. At the instant that the springs 67 and 68 are driven into contact an energizing circuit for the release-magnet 39 is set up through the springs 179 and 180 at the connector-switch D. The said springs are controlled by a release-relay 180^a and the former of said springs is connected to ground and normally in contact with the spring 180. The energizing current flows from ground G² at the connector D and through the springs 179 and 180, third trunk-conductor 181, relay 74, individual bank-springs 68 and 67, conductor 182 and release-magnet 39 to the battery-lead 178 and to the nongrounded terminal of battery B and to ground G. The said release-magnet 39 then attracts its armature 55 and locks the plunger-arm 41 in a position shown by the full lines in Fig. 2, and at the same time separates the springs 56 and 57, respectively, from the springs 58 and 59. The object in separating the springs 52 and 53 after the armature 49 is attracted is to destroy the circuit that supplies the magnet 38 with a strong magnetizing current, since after the said armature is once attracted and in contact with the pole-piece the first energizing circuit is sufficiently strong to maintain it there until the magnet 39 is energized. But even this weak energizing circuit through the said magnet 38 is destroyed when the magnet 39 separates the springs 57 and 59. It is obvious that it will be useless to maintain said energizing circuit, since the armature 62, as shown in Fig. 2, retains the arm 41 in its operative position. When the springs 58 and 56 are separated at the same time the energizing circuit through the auxiliary-relay 63 is destroyed and the off-normal lamp 66 goes out. The object in providing said lamp will be made clear. Therefore, the simple raising of the subscriber's switch-hook operates the individual-switch A, so that the magnet 38 operates the plunger 42, which latter in turn energizes the release-magnet 39 to retain the armature 41 depressed, and to destroy the energizing circuit through itself. Maintaining the plunger 42 in this position in the bank E, as described, and thereby maintaining the springs 69 and 70, respectively, in contact with the springs 72 and 71, extends the subscriber's line to the conductors 183 and 184, and, therefore, to the connector D, as clearly shown in Fig. 3. The energizing circuit 4 for the release-magnet 39 being provided through the magnet 74 as long as the said magnet 39 is energized, the magnet 74 will be energized also, and a guarding potential will, therefore, be maintained at the contact-point 94 to prevent the master-switch from placing the idle wipers opposite the seized trunk- 130

line, so that no other subscriber may be able to seize upon the said line. Upon the establishment of said guarding potential the auxiliary-relay 89 is energized simultaneously with the circuit controlling relay 88. The energizing of the latter closes an energizing circuit through the motor-magnet 83, so that the armature 82 is attracted once and the wiper 47 driven onto the contact-point 185. If the said contact is also busy the said wiper will be driven onto the next contact for the same reason and so on until the wiper 47 arrives on a contact that is without guarding potential. The object of providing the relay 89 is as follows: Assume that before the individual switch A seizes the trunk-line that corresponds to the contact-point 94 the immediately succeeding half dozen contacts, for example, are busy, then when the said trunk is seized, as described, the wiper 47 will be driven onto the first busy contact 185 and from busy contact onto busy contact until an idle contact is found. It requires some little time to accomplish this, and to prevent in the meanwhile any other subscriber from energizing his trip-magnet and thereby seizing one of the said busy trunk-lines, all of the trip-magnets corresponding to the trip-magnet 38 of the group to which the individual-switch A belongs are temporarily disconnected from the ground terminal G^1 which is common to all of the individual-switches of the same group. And in this manner the busy trunk-lines are protected against seizure by calling subscribers at the time that the master-switch-wiper 47 may be passing over the contact-points corresponding to said busy trunk-lines. The energizing circuit for the said relays 88 and 89 is from ground G^3 through the said relays 88 and 89 to the common plate 75, through the wiper 47 to the contact-point 94 (when the trunk-line is first seized) through the springs 95 and 96 to the battery-lead 178, and to the non-grounded terminal of battery B and to ground G. The energizing circuit for the motor-magnet 83 is from ground G^4 through the springs 86 and 87 and through the said magnet to the springs 85 and 84 and to the battery B. Having, therefore, established connection with the connector D the subscriber then begins by turning his dial first for the number 2, thereby grounding the vertical-line-conductor 177 twice, and then after that the rotary-line-conductor 176 once. Grounding the vertical-line-conductor twice energizes the vertical-line-relay 118 of the connector twice and a current passes from ground G^5 through the ground-springs 14 and 17, ground-post 5, vertical impulse-spring 4, vertical-line-conductor 177, individual bank-springs 69 and 72, vertical-trunk-conductor 183, vertical-line-relay 118, winding 186 of the differential-relay 120 to the battery-lead 178 and to the non-grounded terminal of battery B and to ground G. Not only is the vertical-line-relay 118 energized, but the differential-relay 120 as well; but at this stage of the operation said energization of the differential-relay 120 is of no significance. The line-relay 118 being energized twice the line-relay-springs 122 and 123 are pressed into contact twice, thereby establishing an energizing circuit each time through the vertical-magnet 113 from ground G^6 , through the said line-springs and through the private-springs 128 and 127, side-switch-wiper 150, contact-point 154, vertical-magnet 13 to the battery-lead 178 and to the non-grounded terminal of battery B and to ground G. Being energized twice the vertical-magnet 113 attracts its armature twice and thereby raises the shaft 97 two steps thereby placing the switch-shaft-wipers 98, 99 and 100 opposite the first contact of the second level of their respective banks. The grounding of the rotary-line-conductor 176 that follows energizes the rotary-line-relay 119 once through a circuit that extends from ground G^7 and through the ground-post 5, rotary impulse-spring 7 and rotary-line-conductor 176 to the individual-switch bank-springs 70 and 71, thence over the rotary-trunk-conductor 184 and through the rotary-line-relay 119, winding 187 of the differential-relay 120, back-bridge-relay-springs 176^a and 175 to the battery-lead 178 and to the non-grounded terminal of battery B and to ground G. Said line-relay upon attracting its armature forces the line-relay-springs 126 and 123 into contact and thereby energizes the private-magnet 116 over a circuit that extends from ground G^8 through the said line-springs and the private-magnet 116 and through the back-bridge-relay-springs 176^a and 175 to the battery-lead 178 and to the non-grounded terminal of battery B and to ground G. Energizing the private-magnet once permits the side-switch retracting-spring 170 to draw the side-switch into second position and to place the side-switch-wiper 150 in contact with the side-switch contact-point 155^a. Shifting said side-switch, when the vertical-line-conductor 177 is grounded ten times for the digit "0", causes the vertical-line-relay 118 to energize the rotary-magnet 114 instead of the vertical-magnet 113 each time that the line-relay-springs 122 and 123 are pressed into contact. The energizing current for said rotary-magnet 114 passes from the ground terminal G^9 , as before, to the side-switch-wiper 150, but then it extends from the contact-point 155^a and through the rotary-magnet 114 to the battery-lead 178 and to the non-grounded terminal of battery B and to ground G. The said rotary-magnet being energized ten times attracts its armature ten times, so that

the pawl 144 rotates the shaft 97 step-by-step ten places, thus placing the line-wipers 98 and 99 in engagement with the called subscriber's normal-conductors 188 and 189, and 5 the private-wiper 100 with the private-normal-conductor 190. In the same manner that the normal-conductors 188 and 189 connect the called subscriber's line with the connector-line-bank 101 the conductors 191 10 and 192 connect the calling subscriber's line-conductors 177 and 176 with the proper connector-line-bank. In a similar manner that the private-normal-conductor 193 connects the individual bank-spring 67 with the proper connector-private-bank-contacts, the 15 private-normal-conductor 190 connects the corresponding bank-spring of the called individual-switch A¹ with its connector-private-bank-contacts. When the rotary-line-conductor 176 is grounded once for the last time the private-magnet 116 of the connector is operated once more as before. As a result the side-switch F is then drawn into third position by the retracting-spring 170 20 and the side-switch-wipers 150, 151, 152 and 153 pass into engagement with the contact-points 159, 160, 161, and 162, respectively. The engagement of the side-switch-wipers 152 and 153 with the corresponding contact-points 161 and 162 connects the subscribers' 25 extended conductors 183 and 184 with the called subscribers' normal-conductors 188 and 189, respectively, the former through the condenser 194 and the latter through the condenser 195. The engagement of the side-switch-wiper 151 with the contact-point 160 places a guarding potential at the private-wiper 100 and, therefore, at the private-bank-contact with which said wiper is in 30 engagement, and at all other private-bank-contacts connected in multiple thereto, so as to protect the called line from further seizure. The subscriber having thus extended his line into connection with the called subscriber's line, he may now signal the latter subscriber by pressing the signaling-button 30, thereby grounding the vertical-line-conductor 177 when the spring 31 engages the contact-point 33. As a result the vertical-line-relay 118 of the connector is energized; 35 but since the side-switch-wiper 150 is in third position the ringer-relay 117 is energized when the line-relay-springs 122 and 123 are pressed into contact. The energizing current passes from ground G^a to the side-switch-wiper 150, thence through the contact-point 159, ringer-relay 117, differential-relay-springs 174 and 173 to the battery-lead 178 and to the non-grounded terminal 40 of battery B and to ground G. It is here, it will be evident, that the energization of the differential-relay 120 is useful for the first time by maintaining the springs 174 and 173 in contact whereby the ringer-relay 45 117 may be energized. The said differential-relay has been energized in series with the rotary-line-relay 119 each time that an energizing circuit has been established through said relay, but to no purpose. The ringer-relay being energized, as stated, a 50 current is sent over the normal-conductors 188 and 189 to the called subscriber's station and the bell of said subscriber is rung. The said current passes from the ringer-generator 136 through the ringer-relay-springs 135 and 132, side-switch-wiper 152, contact-point 161, vertical-line-wiper 98, vertical-normal-conductor 188, vertical-line-conductor 195^a, condenser 196, ringer 197, springs 198 and 199, rotary-line-conductor 200, rotary-normal-conductor 189, rotary-wiper 99, contact-point 162, side-switch-wiper 153 and ringer-relay-springs 131 and 134 to the generator 136. The called subscriber upon removing his receiver 201 permits the springs 202 and 203 to come into contact and an energizing circuit is established through the back-bridge-relay 121. The current in said circuit flows from ground G⁷ to the side-switch-wiper 151, thence through the winding 204 of the relay 121 to the ringer-relay-springs 133 and 131, side-switch-wiper 153, rotary-line-wiper 99, rotary-normal-conductor 189, rotary-line-conductor 200, primary winding 205 of the induction-coil 206, transmitter 207, and through the springs 202 and 203 to the vertical-line-conductor 195^a, thence over the vertical-normal-conductor 188, vertical-line-wiper 98, side-switch-wiper 152, winding 208 of the relay 121 and 100 through the differential-relay-springs 172 and 173 to the battery-lead 178 and to the non-ground terminal of battery B and to ground G. Of course, it will be clear that this circuit is only established when the 105 called subscriber removes the receiver from the switch-hook and after the ringer-relay 117 is deenergized—that is, after the calling subscriber releases his signaling-button 30. The relay 121 being energized the springs 110 176^a and 177^a are forced into contact, and as a result the transmitter 18 of the calling sub-station is provided with current. The current for energizing said transmitter also flows from the ground G⁷ and then passes 115 through the springs 177^a and 176^a and through the winding 187 of the differential-relay 120 to the rotary-line-relay 119, thence to the rotary-trunk-conductor 184 and to the rotary-line-conductor 176, primary winding 120 20 of the induction-coil 19, transmitter 18, springs 28 and 27 to the rotary-line-conductor 177 and thence to the vertical-trunk-conductor 183, vertical-line-relay 118, winding 186 of the differential-relay 120 to the battery-lead 178 and to the non-grounded terminal 125 of battery B and to ground G. The windings 186 and 187 of the said differential-relay are so made that the current in passing in the direction thus described does 130

not energize said relay. Therefore, the springs 173 and 172 remain in contact. The energizing circuit for the release-magnet 115 is controlled conjointly by the trunk-release-springs 124 and 125 located between the vertical and rotary line-relays 118 and 119, and by the differential-relay-springs 173 and 174, so that although the said line-relays are energized during talking, and 5 although, therefore, the trunk - release - springs 124 and 125 are in contact, the energizing circuit for the release-magnet 115 is still open at the differential-relay-springs 174 and 173. The transmitters of the two 10 subscribers being thus provided with talking battery current, in the manner well-known to all skilled in the art, the subscribers may now communicate with each other. Should the called subscriber's line 15 for any reason be busy at the time that the calling subscriber attempts to close connection with the called line by grounding the rotary-line-conductor 176 and thereby energizing the private-magnet 116, the connector-switch will be released. The said release 20 occurs because the private-wiper 100 is at such a time connected with a grounded terminal of battery B; so that when the private-magnet is energized and the springs 129 25 and 130 are brought into contact the release-magnet 115 is energized. The energizing circuit extends from the battery B to a ground similar to ground G², and through springs of the individual-switch A¹ similar 30 to the spring 67 and 68 of the individual-switch A, and to the tenth contact of the second level of the private-bank 102—that is, if the subscriber #20 has made a call; or 35 through a side-switch-wiper similar to the side-switch-wiper 151 of the connector D (if the subscriber #20 has been called), and through the bank-multiplying-conductors to the tenth contact of the second level of the 40 private-bank 102; then the current passes on to the private-wiper 100, side-switch-wiper 151, contact-point 156^a (since at the 45 time that the rotary-line-conductor 176 is grounded for the last time the side-switch is in second position), through the private-springs 129 and 130 to the release-magnet 115, and through the differential-relay-springs 174 and 173 to the battery-lead 178 and to the non-grounded terminal of battery B and to ground G. The release- 50 magnet 115 being energized the connector-side-switch F and switch-shaft 97 are restored in a well known manner, leaving the said side-switch in first position and the switch-shaft in normal 55 position. But as soon as the calling subscriber presses his signaling - button he grounds the vertical-line-conductor 177, as stated, and thus energizes the vertical-line-relay 118 and causes the switch-shaft 97 to 60 be raised one step. The switch-shaft-springs 65 110 and 109 now close into contact again and a busy signaling current is sent to the calling subscriber's line, notifying the said subscriber that the line he desires is busy. Said busy current may be generated in the coil 70 209 in any suitable manner known to the art one end of which coil is connected to the battery-lead 178. The busy signaling current passes from the said coil 209 through the said springs 110 and 109 to the side-switch-wiper 75 153, thence through the condenser 195 and rotary-trunk-conductor 184 to the rotary-line-conductor 176, through the primary winding 20 of the induction-coil 19, vertical-line-conductor 177, vertical-trunk-conductor 183, vertical-line-relay 118, winding 186 of the differential-relay 120 to the battery-lead 178 and back to the coil 209. The calling subscriber then restores his receiver 80 to the switch-hook and grounds both the vertical and rotary line-conductors 177 and 176 by causing the release-springs 34, 35 and 36 to be pressed into contact. The said line-conductors being thus grounded the vertical and rotary line-relays 118 and 119 of the 85 connector-switch D are energized simultaneously; and not only are the said relays energized, but the differential-relay 120 as well. The current through each of the windings of the said differential-relay passes in such a 90 direction that the said coils reinforce or augment each other. The current through the winding 186 of said differential-relay passes from ground G⁵ to the release-spring 34 and through the release-spring 35 to the 95 vertical-line-conductor 177, thence through the connector - vertical - line - relay 118 and winding 186 of the differential-relay 120 to the battery-lead 178 and to the non-grounded 100 terminal of battery B and to ground G. 105 Through the winding 187 the current passes from ground G⁵ to the release-spring 34, thence through the springs 35 and 36 to the rotary-line-conductor 176 and through the rotary-line-relay 119, winding 187 and back-bridge-relay-springs 176^a and 175 to the battery-lead 178 and to the non-grounded terminal of battery B and to ground G. When 110 the said line-relays 118 and 119 are energized the springs 124 and 125 are pressed into contact, and since the differential-relay-springs 174 and 173 are in engagement at the same time the release-magnet 115 is energized in series with the release-relay 180^a. The said relay 180^a upon attracting its armature separates the springs 179 and 180, and as a result the energizing circuit through the trunk-release-conductor 181, relay 74, individual bank-springs 68 and 67, and through the release - magnet 39 of the individual-switch A, is then destroyed. The result is that the guarding potential at the master-switch contact-point 94 is removed at the instant that the springs 95 and 96 regain their 115 normal positions, whereby the control over 120 125 130

the trunk-conductors 183 and 184 is abandoned; and at the same time the release-magnet 39 being deenergized permits the release-armature 55, under the tension of the springs 56 and 57, to disengage from the terminal 60 of the plunger-arm 41, and as a result the retracting-spring 44 restores the plunger 42 to normal position and permits the subscribers' line-conductors 177 and 176 to be disconnected from the trunk-line-conductors 183 and 184; and also, by the removing of said plunger, the trunk-release-springs 67 and 68 are forced apart in order that the energizing circuit through the release-magnet 39 may not be reestablished when the connector-release-relay 180^a is deenergized. The energization of the release-magnet 115, as described, produces a restoration of the connector-switch-shaft and side-switch, and as soon as the individual bank-springs 69 and 72 and 70 and 71 separate, then all the energized magnets of the connector are restored also, wherefore all the switches are fully restored to normal condition. It has been described that when the subscriber #50 established connection with the line of the subscriber #20 a guarding potential was established at the private-wiper 100 and, therefore, at the private-normal-conductor 190. This guarding potential not only protects the called line from further seizure, as described, but causes an energizing circuit to be established through the bridge-cut-off or release-magnet 210 of the individual-switch A¹, so as to cause said release-magnet to attract its armature 211 for the purpose of separating the springs 212 and 213 from the springs 214 and 215, respectively. In this manner the said release-magnet 210 is made to act as a bridge-cut-off-relay, whereby the energizing circuit for the trip-magnet 216 is destroyed in order that when the called subscriber removes his receiver from the switch-hook the individual-switch A¹ of the called line may not be operated to interfere with the connection established. Also, by separating the springs 212 and 214, the auxiliary-relay 217 is prevented from energizing uselessly and from causing the lamp 218 to be lighted unnecessarily. After the subscribers are through communicating, if the calling subscriber restores his receiver to his switch-hook he will restore the switches as before, but the circuits employed in the lease are slightly different from the circuits pointed out in the preceding. For instance, when the calling subscriber restores his receiver to the switch-hook the cam-arm 10 engages the spring 25 and thereby causes the springs 27 and 28 to separate before the cam-arm 9 forces the release-spring 34 onto the release-spring 35. As soon as the said springs 27 and 28 spring apart the energizing circuit through the transmitter 18 and, therefore, through the vertical and rotary line-relays 118 and 119 is destroyed. The said relays then regain their normal positions, but immediately after the ground-release-spring 34 is forced onto the vertical-release-spring 35, thereby grounding the vertical-line-conductor 177, causing the vertical-line-relay 118 and the differential-relay 120 to be energized. The latter relay upon energizing forces the springs 173 and 174 into contact and thereby closes one of the normally open switch-points in the energizing circuit of the release-magnet 115. As soon as the differential-relay-springs 172 and 173 are separated the back-bridge-relay 121 is deenergized, which latter then permits the springs 175 and 176^a to come into contact. Meanwhile the switch-hook has descended far enough to press all the release-springs into contact and to ground the rotary-line-conductor 176 also. As a result the rotary-line-relay 119 is energized and a current is sent through the winding 187 of the differential-relay 120, which strengthens the already energized differential-relay. The vertical and rotary line-relays 118 and 119 being energized at the same time the trunk-release-springs 124 and 125 are closed in contact, whereby the last normally open switch-point in the energizing circuit of the release-magnet 115 is closed. The said release-magnet receives current then from ground G⁶ through the trunk-release-springs 124 and 125, release-relay 180^a, through the said release-magnet and differential-relay-springs 174 and 173 to the battery-lead 178, to the non-grounded terminal of battery B and to ground G. It will be evident that both the release-magnet 115 and release-relay 180^a are energized simultaneously. The effect of energizing the latter relay has already been described—that is, the individual-switch A is restored to normal position and a guarding potential at the master-switch bank-contact 94 is removed. At the same time the connector-switch-shaft and side-switch and relays and magnets are restored to normal condition. The object of providing the auxiliary-relay 63 and the lamp 66 at the individual-switch is to indicate at the central office whenever the vertical-line-conductor 177 becomes grounded in case of accident. The relay 63 would be energized by current flowing from ground to said vertical-line-conductor 177, thence through the springs 56 and 58 and the said coil 63 to the battery-lead 178 and to the non-grounded terminal of battery B and to ground G. Said relay will then attract its armature and cause the lamp 66 to flash and stay lighted as long as the said ground remains on the line. One of said relays is usually provided for a group of individual-switches numbering ten, twenty, fifty, or even one-hundred or more if desired. Since it is absolutely essential that the longitudinal slot upon the plunger- 130

shaft 45, near which all of the individual-switches are arranged, should not rotate beyond a point that will make it impossible for the butt end 48 of the plunger 42 to return to its socket at any time, the oscillations of said shaft are, therefore, so controlled by the pins 77, 78, 79 and 80 upon the ratchet-wheel 76 of the master-switch C that if a plunger leaves the plunger-shaft at one extreme position and then tries to return when the said shaft is at the opposite extreme position it will find no difficulty in adjusting itself in proper contact therewith. Care is taken that the said pins on the ratchet-wheel 76 shall oscillate the cam 46 just so far and no farther. Having fully described my improved individual-switch it will be evident that it is adapted to be used not only for common battery work but for local battery work as well. One of the features is the provision of the quick-acting armature 50 for the trip-magnet 38, and of the more slowly acting armature 49 that is attached to the plunger-arm 41. The armature 50 first operates and then provides a stronger energizing circuit for operating the armature 49, which latter armature being attracted connects the calling subscriber's line with any desired trunk-line, depending upon the position to which the plunger-shaft 45 has rotated or positioned all idle plungers. An energizing circuit is then, as a result, established for the release-magnet 39, which latter in turn operates to destroy the energizing circuit through the original magnet 38.

The magnets employed in my improved individual-switch may be wound to any suitable strength. For instance, the trip-magnet 38 may be wound to 100 ohms; the bridge-cut-off and release-magnet 39 to 1000 ohms; the release-trunk-relay 74 to 60 ohms; the ground signal relay 63 to one ohm; and in the master-switch the motor-magnet 83 to 60 ohms, the circuit controlling relay 88 to 1000 ohms, and the auxiliary-relay 89 to 1000 ohms.

It will be understood, of course, that the exchange can be enlarged by interposing one or more selectors between the individual-switches and the connectors, in the well-known manner. For convenience of illustration, however, I have elected to show the individual-switch, trunk-lines running direct to connectors, thus illustrating a comparatively small exchange in which each subscriber's number consists only of two digits. Should the exchange be enlarged to accommodate more subscribers, necessitating the use of three digit numbers, then selectors would be used between the individual-switches and the connectors. A still further enlargement, necessitating the use of four digit numbers, would require first and second selectors. All this, however, will be

readily understood and need not be further described.

With my improved arrangement the subscribers' individual-switches are operated automatically when the subscribers start to call, the mere closure of the metallic line-circuit at any calling subscriber's station being sufficient to initiate the operation of the calling subscriber's individual-switch, thus automatically placing his line in connection with the pre-selected idle trunk-line. In this way, the preliminary trunking has all been accomplished by the time the calling subscriber begins calling the number of the called subscriber's substation. During conversation the calling subscriber's individual-switch remains energized by the temporarily closed local circuit through the magnet 39, which latter must be deenergized when it is desired to restore the individual-switch and thus vacate the trunk-line temporarily appropriated for use between the individual-switch and the connector or other switch. With the arrangement shown, it will be seen that this local circuit for maintaining the energized condition of the magnet 39 during conversation is controlled by the relay 180^a, which latter is energized when the line-relays 118 and 119 and the differential-relay 120 are energized by the act of the calling subscriber in hanging up his receiver. As illustrated, there is a relay 180^a for each connector. The relays 74 are, however, each individual to one of the trunk-lines running from the group of individual-switches to the connectors or other switches, and consequently these relays 74 are each individual to one of the contacts in the master-switch. Each relay 74 when energized places a guarding potential at its allotted bank-contact in the master-switch or switch-operating machine employed for selectively operating the different individual-switches of the group to which it belongs. In this way, the guarding potential for the master-switch comes from the non-grounded pole of the battery, while in the connector shown the guarding potential for producing the automatic busy release in case the called line is busy comes from the grounded pole of the battery. The battery B is normally bridged across the terminals of each subscriber's line. For example, the calling subscriber's line has one side normally connected with the grounded pole of the battery through the medium of the magnet 38, which is individual to such line, and has the other side thereof normally connected with the non-grounded pole of the battery through the medium of the relay 63, which latter is common to all of the lines in the group. In this way, the line-energizing circuit for initially actuating the individual-switch includes the calling sub-

scriber's transmitter 18, the primary of the induction-coil, the contacts of the push-button 30, and the contacts of the hook-switch, as previously described. The battery bridge 5 thus normally existing across the end or terminal of each subscriber's line is controlled by the magnet 39 allotted to such line. Of course, it will be understood that these bridges are not individual to the lines, inasmuch as each bridge includes the battery 10 B, which latter, of course, is common to all of the lines in the exchange, or at least common to all of the lines in the group. During conversation, however, the battery is in bridge of the talking circuit through the medium of relays allotted to the connector. My improved trunking apparatus and machinery for enabling a calling subscriber to automatically obtain connection 15 with a pre-selected trunk-line, or with any other idle trunking or trunk-like connection, before calling the desired number or before giving the order for the desired number, can be used in either automatic or semi-automatic exchanges and in connection with either automatic or manual switchboard apparatus for completing the connections in accordance with the called number. In any event, however, and particularly 20 if the system is of the common battery type, the said battery is normally in bridge of each subscriber's line, and this bridging is through the medium of the said trunking machinery or apparatus. In other words, the battery is preferably normally connected with both sides of the subscriber's line through the medium of certain coils or windings of the automatic trunk-selecting and connecting apparatus in which the subscribers' lines terminate. In my improved 25 arrangement there are only two electro-magnets which are individual—that is to say, each subscriber's line has allotted to it only two electro-magnets, thus materially simplifying the trunking apparatus. Economy 30 and efficiency are obtained by adapting each magnet to act not only as a relay but also as an actuating-magnet, whereby each magnet not only controls certain circuits, but also has a certain degree of control over the plunger. 35

With my improved arrangement an accidental or abnormal grounding of a subscriber's line will not operate the individual-switch of such line. In other words, each individual-switch is operated by a line-circuit including both sides of the line in series—that is to say, a metallic circuit is used for initiating the operation of the individual-switch. Consequently, as stated, the accidental or abnormal grounding of one or more subscribers' lines will not throw the individual-switches into operation, and will not temporarily tie up any trunk-lines. 40

Such accidental or abnormal grounding of the lines will be instantly indicated by the supervisory lamp-signal 66, it being understood that one of these lamps can be allotted to each group of subscribers. It will also be seen that each group of subscribers can be divided into sub-groups, and another lamp allotted to each sub-group, thus rendering it comparatively easy to find the lines which are grounded. The selectors and connectors or any other switching machinery which may be provided are subsequently operated by grounded line-circuits—that is to say, after the operation of the individual-switch by the calling subscriber, through the medium of the metallic circuit, all subsequent switching operations are accomplished by grounded line-circuits which include the ground between the exchange and the substation of the calling line. Thus, grounded circuits can be used for operating all of the switching machinery except the switching device for making the first selection of an idle trunk-line, and for this first switch a metallic energizing circuit can be provided, thus precluding the liability of one or more of the trunk-lines leading from the individual-switches being temporarily tied up by the accidental or abnormal grounding of one or more of the subscribers' lines. In other words, if grounded circuits are used for initiating the operation of the individual-switches, it naturally follows that an accidental or abnormal grounding of any line will operate the individual-switch thereof, causing the latter to make connection with the selected trunk-line, thus keeping this selected trunk-line out of use until the trouble can be remedied. With my improved arrangement, however, as explained, the trunk-lines leading from the individual-switches are not subject to this kind of trouble. 50

What I claim as my invention is:

1. A telephone system comprising a calling subscriber's line-conductors normally open at the subscriber's station, idle trunk-lines, and an automatic selectively operated individual-switch allotted to the subscriber's line, adapted for connecting the line with any one of said idle trunk-lines, means for maintaining said switch normally ready and selectively positioned to perform the said connection whenever the subscriber closes his line-conductors together and thereby sends electric current through the individual-switch. 110

2. A telephone system comprising a calling subscriber's line-conductors normally open at the subscriber's station, idle trunk-lines, and an automatic selectively operated individual-switch provided with a terminal bank to which the said trunk-lines are connected, said individual-switch adapted to be 120

operated by the said subscriber for connecting his line with any one of said idle trunk-lines, means for maintaining said switch normally ready and selectively positioned to make the said connection whenever the subscriber closes his line-conductors together and thereby sends electric current through the individual-switch.

3. A telephone system comprising a calling subscriber's line-conductors normally open at the subscriber's station, and terminating at the other end in an individual switch, a plurality of trunk-lines, a switching device capable of establishing connection 10 between the said subscriber's line and any one of said trunk-lines, comprising means for searching for an idle trunk-line and means for maintaining said switch normally ready and selectively positioned to make the 15 said connection whenever the subscriber closes his line-conductors together and thereby sends electric current through the individual-switch.

4. A telephone system comprising a calling subscriber's talking circuit conductors normally open at the subscriber's station, trunk-lines, a subscriber's individual-switch provided with a plunger and plunger-controlling magnet, a terminal for each trunk 20 and a corresponding line terminal for each trunk in said switch, and an energizing circuit for said magnet, comprising the talking circuit conductors, whereby the said magnet may be energized to positively operate and cause said plunger to connect the 25 said line with any one of said trunk-lines.

5. A telephone system comprising a calling subscriber's talking circuit conductors normally open at the subscriber's station, 30 idle trunk-lines, and an individual-switch provided with a terminal bank, a plunger adapted to be thrust into said bank, a plunger-controlling magnet for operating said plunger, and an energizing circuit for 35 said magnet, comprising the talking circuit conductors, each of said trunk-lines terminating in suitable contacts in said bank, and the subscriber's line terminating in contacts common to the 40 said trunk-lines but out of engagement therewith, whereby the said line may be connected with one of said trunk-lines.

6. A telephone system comprising a calling subscriber's line-conductors normally 45 open at the subscriber's station, idle trunk-lines, an individual-switch provided with a plunger, a plunger-controlling magnet, and a plurality of energizing circuits for said magnet, one including the two line- 50 conductors in series, whereby the said line and one of said trunk-lines may be connected by said plunger.

7. A telephone system comprising a calling subscriber's line-conductors normally 55 open at the subscriber's station, a plurality

of trunk-lines, a switching device provided with a plunger capable of being operated to establish connection between the said subscriber's line and any one of said trunk-lines, said plunger being controlled by a 70 plunger-controlling trip-magnet, and a plurality of energizing circuits for said magnet, one comprising the said line-conductors, and the other a local circuit controlled by said magnet itself.

8. A telephone system comprising a calling subscriber's line-conductors normally open at the subscriber's station, trunk-lines, a subscriber's individual-switch provided with a plunger and plunger-controlling 75 magnet, a terminal for each trunk and a corresponding line terminal for each trunk, an energizing circuit for said magnet, comprising the line-conductors in series, the said magnet adapted to be energized to 80 operate and cause said plunger to connect the said line with any one of said trunk-lines, said individual-switch allotted to said subscriber's line, said plunger normally ready and in position to perform the said 85 connection whenever the subscriber closes his line-conductor and thereby sends the electric current for energizing said magnet.

9. A telephone system comprising a calling subscriber's line-conductors normally 90 open at the subscriber's station, idle trunk-lines, and an individual-switch provided with a terminal bank, a plunger adapted to be thrust into said bank, a plunger-controlling magnet for operating said plunger, 95 an energizing circuit for said magnet, comprising the line-conductors in series, each of said trunk-lines terminating in suitable contacts in said bank, and the subscriber's line terminating in contacts common to the 100 said trunk-lines but out of engagement therewith, whereby the said line may be connected with one of said trunk-lines, said plunger normally ready and in position to 105 perform the aforesaid connection whenever the subscriber closes his line-conductors and thereby sends electric current for energizing 110 the said magnet.

10. In an automatic telephone system, a subscriber's line and a trunk-line, an individual-switch provided with a plunger for connecting the said subscriber's line with the said trunk-line, a release-magnet, and a plunger-controlling magnet provided with a couple of circuits, one circuit including 115 the subscriber's line-conductors in series, and the other circuit being local and controlled by the said plunger-controlling magnet itself.

11. In an automatic telephone system, a 120 calling subscriber's line and a plurality of trunk-lines, a trunk-release-conductor allotted to each trunk-line, an individual-switch provided with a bank in which the said subscriber's line and trunk-lines and trunk- 125

- release-conductors terminate, said individual-switch also provided with a plunger, a plunger-controlling magnet, and a release-magnet, said plunger adapted when the said 5 plunger-controlling magnet is energized to connect the said subscriber's line with one of said trunk-lines, a couple of energizing circuits for the said plunger-controlling magnet, one circuit controlled directly by 10 the subscriber and comprising the subscriber's line-conductors in series, and the other circuit being local and controlled by the said release-magnet, whereby when the subscriber goes to make a call the said plunger-controlling magnet is energized to connect 15 the said subscriber's line with the said trunk-line, an energizing circuit for the said release-magnet, comprising the said trunk-release-conductor, together with a master-switch for selectively controlling the plunger of the said individual-switch to maintain the same when out of use in such position that the subscriber's line will be connected with an idle trunk-line when he calls, 20 and whereby the energizing circuit of the plunger-controlling magnet is so controlled that the said plunger can never connect the subscriber's line with a busy trunk-line.
12. In a telephone system, the combination of subscribers' telephone lines, subscribers' selectively operated individual trunking switches, trunk-lines leading from the said individual-switches, a common battery normally in bridge of each telephone 30 line through the medium of said individual-switches, means in said switches for disconnecting both poles of the battery from the subscribers' lines, and a common mechanism for controlling the selective operations of 35 said individual switches.
13. In a telephone system, a group of subscribers' telephone lines, automatic switches located at the exchange and controlled by the subscribers, adapted to enable a calling 40 subscriber to establish connection with the called subscriber's line, and a source of switch-operating electric current normally in bridge of each subscriber's telephone line, adapted for use by any calling subscriber in 45 automatically switching his line into connection with the called subscriber's line, and a common mechanism for controlling the trunking operations of said automatic switches.
- 50 14. In a telephone system, a line, a selectively operated individual trunking switch for said line provided with an operating magnet having a quick acting armature and a slow acting armature, a circuit-closing 55 plunger operated by one armature, and a circuit controlled by the other armature, trunking circuits associated with said plunger, any one of which may be closed by said plunger as a result of the first closure of the 60 line circuit.
15. In a telephone system, a line, a selectively operated individual trunking switch for said line provided with an operating magnet having a quick acting armature and a slow acting armature, a circuit-closing 70 plunger operated by one armature, and the circuit of same magnet controlled by both armatures, trunking circuits associated with said plunger, any one of which may be closed by said plunger as a result of the 75 first closure of the line circuit.
16. In a telephone system, the combination of a subscriber's line, an operating magnet provided with a pair of armatures, a bridge normally across the line, a combined 80 release and bridge-cut-off magnet, circuit-closing means to be released by said bridge-cut-off magnet, and a couple of energizing circuits for the said operating magnet, one energizing circuit including the subscriber's 85 line, subject to control by the said bridge-cut-off magnet, and the other energizing circuit controlled by the said pair of armatures, substantially as set forth.
17. In a telephone system, a group of subscribers' telephone lines, automatic switching machinery controllable by the subscribers, grounded circuits for operating said switching machinery, a relay adapted to be energized by the grounding of any 90 line, and a lamp-signal provided with a normally open circuit controlled by said relay, whereby accidental or abnormal grounding of any line is indicated by said lamp-signal.
18. In a telephone system, the combination of a group of subscribers' lines, trunk-lines, automatic trunk-selecting and connecting switches controllable by the subscribers, a relay common to said subscribers' lines, adapted to be energized by a circuit including 100 any one of said lines, a lamp-signal provided with a normally open circuit controlled by said relay, and means for disconnecting said relay from any line in use.
19. In a telephone system, a group of subscribers' telephone lines, automatic switching apparatus controlled by the subscribers, a signal associated with said switching apparatus, common to all of said lines, adapted to automatically indicate the presence of 110 an accidental or abnormal ground on any line, a relay for controlling said signal, and means for disconnecting said relay from any line in use.
20. In a telephone system, the combination of subscribers' telephone lines, individual trunking switches for said lines, a grounded battery for operating said switches, a signaling device adapted to automatically indicate the presence of an accidental or abnormal ground on any line, a relay for controlling said signal, and means for disconnecting said relay from any line in use.
21. In a telephone system, individual- 130

switches, a master-switch having bank-contacts, a plurality of trunk-lines, one for each bank-contact, each trunk-line provided with a third conductor or release-trunk, relays 5 for said release-trunks, each relay having its winding included in its allotted release-trunk, a battery having one pole grounded, and circuits by which any relay when energized connects its corresponding bank-contact with the non-grounded pole of said battery, establishing a non-grounded guarding potential at such contact.

22. In a telephone system, the combination of a subscriber's line, an individual-switch provided with an armature, releasing means, a bridge, a combined release and bridge-cut-off-magnet, an operating magnet for said armature, said bridge-cut-off magnet provided with means for locking said armature in its normal position, adapted 15 also for locking said armature in its attracted position.

23. In a telephone system, the combination of a subscriber's line, an individual-trunking switch therefor, a bridge normally across said line, releasing means, said switch provided with a combined bridge-cut-off and releasing magnet, a plunger-arm adapted to be locked in normal position by the 25 said magnet when any subscriber calls the said line, said magnet also adapted to lock said arm in operative position whenever said individual-switch is used for making a call.

24. In a telephone system, subscribers' 35 lines, a plurality of trunks, means for selecting idle trunks ahead of the calls, automatic means for connecting calling subscribers' lines with the preselected trunks, and energizing circuits by which the calling subscribers initiate the operation of said automatic means, each energizing circuit including both sides of a subscriber's line.

25. In a telephone system, a preselected 45 idle trunk line, automatic means for thus selecting the trunk-line ahead of the call, and means comprising an energizing circuit including both sides of a subscriber's line for obtaining connection with said trunk line.

26. In a telephone system, a preselected 50 idle trunk, automatic means for thus selecting the trunk-line ahead of the call, and means comprising an energizing circuit including both sides of a line for obtaining connection with said trunk line.

55. 27. In a telephone system, a plurality of trunks, automatic means for selecting the first idle trunk next in order after the one last in use, whereby each calling subscriber selects a trunk for the next calling 60 subscriber, and means comprising an energizing circuit including both sides of a subscriber's line in series for obtaining connection with the selected idle trunk.

28. In a telephone system, the combina-

tion of a calling subscriber's line-conductors 65 normally open at the subscriber's station, idle trunk-lines, an automatic selectively operated individual-switch allotted to the subscriber's line, adapted for connecting the line with any one of said idle trunk-lines, means 70 whereby said switch is selectively positioned and normally ready to perform the said connection whenever the subscriber closes his line-conductors together and thereby sends electric current through the individual-switch, and means having vertical motion to select groups or divisions of the exchange 75 and rotary motion to connect with a line in the selected group for extending connection from the selected trunk-line in the 80 direction of the called subscriber.

29. In a telephone system, the combination of a calling subscriber's line-conductors normally open at the subscriber's station, idle 85 trunk-lines, an automatic selectively operated individual-switch provided with a terminal bank to which the said trunk-lines are connected, said individual-switch adapted to be operated by the said subscriber for connecting his line with any one of said idle 90 trunk-lines, means whereby said switch is selectively positioned and normally ready to make the said connection whenever the subscriber closes his line-conductors together and, thereby sends electric current through 95 the individual-switch, and means having vertical motion to select groups or divisions of the exchange and rotary motion to connect with a line in the selected group for extending connection from the selected 100 trunk-line in the direction of the called subscriber.

30. In a telephone system, the combination of a calling subscriber's line-conductors normally open at the subscriber's station, a 105 plurality of trunk-lines, a switching device capable of establishing connection between the said subscriber's line and any one of said trunk-lines, comprising means for searching for an idle trunk line, means whereby said 110 means is selectively positioned and normally ready to make the said connection whenever the subscriber closes his line-conductors together and thereby sends electric current through the individual-switch, and means 115 having vertical motion to select groups or divisions of the exchange and rotary motion to connect with a line in the selected group for extending connection from the selected trunk-line in the direction of the 120 called subscriber.

31. In a telephone system, the combination of a calling subscriber's talking circuit conductors normally open at the subscriber's station, trunk-lines, a subscriber's individual-switch provided with a plunger and plunger-controlling magnet, an energizing circuit for said magnet, a terminal for each

- trunk and a corresponding line terminal for each trunk in said switch comprising the talking circuit conductors, whereby the said magnet may be energized to positively 5 operate and cause said plunger to connect the said line with any one of said trunk-lines, and means having vertical motion to select groups or divisions of the exchange and rotary motion to connect with a line in 10 the selected group for extending connection from the selected trunk-line in the direction of the called subscriber.
32. In a telephone system, the combination of a calling subscriber's talking circuit 15 conductors normally open at the subscriber's station, idle trunk-lines, an individual-switch provided with a terminal bank, a plunger adapted to be thrust into said bank, a plunger-controlling magnet for operating 20 said plunger, an energizing circuit for said magnet, comprising the talking circuit conductors, each of said trunk-lines terminating in suitable contacts in said bank, and the subscriber's line terminating in contacts 25 common to the said trunk-lines but out of engagement therewith, whereby the said line may by the operation of the plunger be connected with one of said trunk-lines, and means having vertical motion to select 30 groups or divisions of the exchange and rotary motion to connect with a line in the selected group for extending connection from the selected trunk-line in the direction of the called subscriber.
33. In a telephone system, the combination of a calling subscriber's line-conductors normally open at the subscriber's station, idle trunk-lines, an individual-switch provided with a plunger, a plunger-controlling 40 magnet, a plurality of energizing circuits for said magnet, one including the two line-conductors in series, whereby the said line and one of said trunk-lines may be connected by said plunger, and means having 45 vertical motion to select groups or divisions of the exchange and rotary motion to connect with a line in the selected group for extending connection from the selected trunk-line in the direction of the called 50 subscriber.
34. In a telephone system, the combination of a calling subscriber's line-conductors normally open at the subscriber's station, a plurality of trunk-lines, a switching device 55 provided with a plunger capable of being operated to establish connection between the said subscriber's line and any one of said trunk-lines, said plunger being controlled by a plunger-controlling trip-magnet, a plurality of energizing circuits for said magnet, one comprising the said line-conductors, and the other a local circuit controlled by 60 said magnet itself, and means having vertical motion to select groups or divisions of the exchange and rotary motion to connect 65 with a line in the selected group for extending connection from the selected trunk-line in the direction of the called subscriber.
35. In a telephone system, the combination of a calling subscriber's line conductors normally open at the substation thereof, trunk lines, means having vertical motion to select groups or divisions of the exchange and rotary motion to connect with a line in the selected group for extending connection 70 from the selected trunk-line in the direction of the called subscriber, a subscriber's individual-switch for the calling line provided with a plunger and plunger-controlling magnet, a terminal for each trunk and a 80 corresponding line terminal for each trunk in said switch, an energizing circuit for said magnet, comprising the line-conductors in series, the said magnet adapted to be energized to operate and cause said plunger to 85 connect the said line with any one of said trunk-lines, said plunger normally ready and in position to perform the said connection whenever the subscriber closes his line-conductor and thereby sends the electric 90 current for energizing said magnet.
36. In a telephone system, the combination of a calling subscriber's line-conductors normally open at the subscriber's station, idle trunk-lines, means having vertical motion to select groups or divisions of the exchange and rotary motion to connect with a line in the selected group for extending connection from the selected trunk-line in the direction of the called subscriber, an individual-switch for the calling line provided with a terminal bank, a plunger adapted to be thrust into said bank, a plunger-controlling 95 magnet for operating said plunger, an energizing circuit for said magnet, comprising the line-conductors in series, each of said trunk-lines terminating in suitable contacts in said bank, and the subscriber's line terminating in contacts common to the said trunk-lines but out of engagement therewith, whereby the said line may be connected with one of said trunk-lines, said plunger normally ready and in position to 100 perform the aforesaid connection whenever the subscriber closes his line conductors and thereby sends electric current for energizing the said magnet.
37. In an automatic telephone system, the combination of a subscriber's line and a trunk-line, an individual-switch provided with a plunger for connecting the said subscriber's line with the said trunk-line, means having vertical motion to select groups or divisions of the exchange and rotary motion to connect with a line in the selected group 115 for extending connection from the selected trunk-line in the direction of the called subscriber, a release-magnet, and a plunger- 120
- 125

- controlling magnet provided with a couple of circuits, one circuit including the subscriber's line-conductors in series, and the other circuit being local and controlled by 5 the said plunger-controlling magnet itself.
38. In an automatic telephone trunking system, the combination of a calling subscriber's line and a plurality of trunk-lines, a trunk-release-conductor allotted to each 10 trunk-line, an individual-switch provided with a bank in which the said subscriber's line and trunk-lines and trunk-release-conductors terminate, said individual-switch also provided with a plunger, a plunger-controlling magnet, a release magnet, said 15 plunger adapted when the said plunger-controlling magnet is energized to connect the said subscriber's line with one of said trunk-lines, a couple of energizing circuits for 20 the said plunger-controlling magnet, one circuit controlled directly by the subscriber and comprising the subscriber's line-conductors in series, and the other circuit being local and controlled by the said release-magnet, whereby when the subscriber 25 goes to make a call the said plunger-controlling magnet is energized to connect the said subscriber's line with the said trunk-line an energizing circuit for the said release-magnet, comprising the said trunk-release conductor, together with a master-switch 30 for selectively controlling the plunger of the said individual-switch to maintain the same when out of use in such position that 35 the subscriber's line will be connected with an idle trunk-line when he calls, and whereby the energizing circuit of the plunger-controlling magnet is so controlled that the said plunger can never connect the subscriber's line with a busy trunk-line, and means 40 having vertical motion to select groups or divisions of the exchange and rotary motion to connect with a line in the selected group for extending connection 45 from the selected trunk-line in the direction of the called subscriber.
39. In a telephone trunking system, the combination of a subscriber's line, an individual trunking switch therefor, a bridge 50 normally across said line, releasing means, said switch provided with a combined bridge-cut-off and releasing magnet, a plunger-arm adapted to be locked in normal position by the said magnet when any subscriber 55 calls the said line, said magnet also adapted to lock said arm in operative position whenever said individual-switch is used for making a call, and means having vertical motion to select groups or divisions 60 of the exchange and rotary motion to connect with a line in the selected group for extending connection from the trunk seized by the switch in the direction of the called subscriber.
- 65 40. In a telephone trunking system, the

combination of subscribers' lines, a plurality of trunks, means for selecting idle trunks ahead of the calls, automatic means for connecting the calling subscribers' lines with the preselected trunks, energizing circuits 70 by which the calling subscribers initiate the operation of said automatic means, each energizing circuit including both sides of a subscriber's line, and means having vertical motion to select groups or divisions of the 75 exchange and rotary motion to connect with a line in the selected group for extending connection from the selected trunk-line in the direction of the called subscriber.

41. In a telephone trunking system, the 80 combination of means for selecting trunks ahead of the calls, a preselected idle trunk-line, means comprising an energizing circuit including both sides of a subscriber's line for obtaining connection with said trunk-line, means having vertical motion under substation control, to select groups or 85 divisions of the exchange, and rotary motion to connect with a line in the selected group, for extending connection from the selected 90 trunk-line in the direction of the called subscriber, and a calling mechanism for causing the vertical and rotary motion, said mechanism requiring a separate actuation thereof for each digit of the called number, operative 95 to transmit impulses by each operation.

42. In a telephone trunking system, the combination of means for selecting trunks ahead of the calls; a preselected idle trunk, 100 means comprising an energizing circuit including both sides of a line for obtaining connection with said trunk-line, means having vertical motion under substation control, to select groups or divisions of the exchange, and rotary motion to connect with a line in the selected group, for extending connection 105 from the selected trunk-line in the direction of the called subscriber, and a calling mechanism for causing the vertical and rotary motion, said mechanism requiring a separate actuation thereof for each digit of the called number, operative 110 to transmit impulses by each operation.

43. In a telephone trunking system, the 115 combination of a plurality of trunks, automatic means for selecting the first idle trunk next in order after the one last in use, means comprising an energizing circuit including both sides of a subscriber's line for 120 obtaining connection with the selected idle trunk, means having vertical motion under substation control, to select groups or divisions of the exchange, and rotary motion to connect with a line in the selected group, 125 for extending connection from the selected trunk-line in the direction of the called subscriber, and a calling mechanism for causing the vertical and rotary motion, said mechanism requiring a separate actuation 130

thereof for each digit of the called number, operative to transmit impulses by each operation.

44. In a telephone system, trunk-lines, means for automatically selecting idle trunks ahead of the calls, a subscriber's hook-switch, and means operated over a complete metallic talking circuit to seize the preselected idle trunk-line in response to closure of the talking circuit by the hook-switch.

45. A telephone system comprising a calling subscriber's talking conductors normally open at the subscriber's station, idle trunk lines, and an automatic selectively operated individual switch allotted to the subscriber's line, adapted for connecting the line with any one of said idle trunk lines, a terminal for each trunk and a corresponding line terminal for each trunk in said switch, means for maintaining said switch normally ready and in position to perform the said connection through the medium of said trunks whenever the subscriber closes his talking conductors together and thereby sends electric current through the individual switch.

46. A telephone system comprising a calling subscriber's talking conductors normally open at the subscriber's station, idle trunk lines, and an automatic selectively operated individual switch provided with a terminal bank to which the said trunk lines are connected, said individual switch adapted to be operated by the said subscriber for connecting his line with any one of said idle trunk lines, a terminal for each trunk and a corresponding line terminal for each trunk in said switch, means for maintaining said switch normally ready and in position to make the said connection through the medium of said trunks whenever the subscriber closes his talking conductors together and thereby sends electric current through the individual switch.

47. A telephone system comprising a calling subscriber's talking conductors normally open at the subscriber's station, and terminating at the other end in an individual switch, a plurality of trunk lines, a switching device capable of establishing connection between the said subscriber's line and any one of said trunk lines, a terminal for each trunk and a corresponding line terminal for each trunk in said switch, said switch comprising means for searching for an idle trunk line and normally ready and in position to make the said connection through the medium of said terminals whenever the subscriber closes his talking conductors together and thereby sends electric current through the individual switch.

48. A telephone system comprising a calling subscriber's line conductors normally open at the subscriber's station, idle trunk lines, an individual switch provided with a

plunger and plunger-controlling magnet, a terminal for each trunk and a corresponding line terminal for each trunk in said switch, and an energizing circuit for said magnet, comprising both of the said line conductors, whereby the said magnet may be energized to positively operate and cause said plunger to connect certain of said terminals to thereby connect the said line with any one of said trunk lines through the medium of said terminals.

49. In a telephone system, subscribers' stations including calling mechanism, a plurality of trunk lines, two switches, one switch for selecting an idle trunk line independently of any operation of said calling mechanism, and thus extend a connection over said selected trunk to the second switch, a magnet for maintaining said first switch in contact with said trunk, and means including a circuit extending from said second switch for controlling said magnet.

50. In a telephone system, a plurality of automatic switches, trunks to be seized by said switches, a master switch common to said automatic switches, a pair of normally open contacts, means for initially operating said master switch, means for continuing said operation, means including said contacts for controlling said last-mentioned means, and means for controlling said switches over two sides of a line circuit in series.

51. In a telephone system, a plurality of automatic switches, trunks to be seized by said switches, a master switch common to said automatic switches, a motor magnet for operating said master switch, means for initially operating said motor magnet, independent means for continuing said operation after the initial operation, and means for controlling said switches over two sides of a line circuit in series.

52. In a telephone system, a plurality of automatic switches, trunks to be seized by said switches, a master switch common to said automatic switches, a motor magnet for operating said master switch, a relay for initially operating said motor magnet, independent means for continuing said operation after the initial operation, and means for controlling said switches over the two sides of a line circuit in series.

53. In a telephone system, a subscriber's line, a plurality of trunk lines extending therefrom, a line switch for connecting with an idle trunk, a magnet for controlling the operation of said switch, means for controlling said magnet over two sides of the line circuit in series, said line circuit being maintained closed until the calling line is connected to the selected trunk.

54. In a telephone system, a subscriber's line including a pair of talking conductors, trunk lines, means for selecting idle trunk lines ahead of the calls, automatic means

for closing connection with a preselected trunk line, and a circuit for initiating the operation by which said automatic means closes connection with the preselected idle trunk line, said circuit including said talking conductors in series.

55. In a telephone system, a subscriber's line including a pair of talking conductors, trunk lines, means for selecting trunk lines ahead of the calls, an automatic trunking switch, a subscriber's hook switch and a circuit adapted to be closed by the movement of the hook switch to cause the operation of said switch and the seizure thereby of a preselected idle trunk line, said circuit including the two talking conductors of said line in series.

56. In combination a telephone line, a switch associated therewith, pairs of multiply connected terminals of said line at said switch, trunk terminals arranged for engagement with said line terminals respectively, a contact actuating member, means for moving said member in one direction to select a set of contacts, means for moving it in another direction to cause interengagement of the contacts of said set, and a locking device for retaining said set of contacts in their actuated position.

57. In combination, a telephone line, a switch associated therewith, a circular bank of contacts at said switch, said bank comprising contact sets in each of which are

represented terminals of said line and of a trunk line, means whereby, upon the initiation of a call, one of said sets of contacts will be actuated to connect the calling line to an idle trunk, and mechanism including an energized magnet for retaining the contacts of said set in engagement.

58. An automatic telephone system comprising a subscriber's telephone line, a plurality of selector switches, a line switch for said telephone line having access to said plurality of selector switches, a magnet for said line switch, an energizing circuit for said magnet, closed upon the initiation of a call from said telephone line to cause said magnet to operate said switch off normal to connect said telephone line with an idle one of said selectors, means for opening the said circuit when said line switch has connected with said idle selector, a release relay for said line switch energized by the initial movement of said line switch off normal, and means under the control of the subscriber at said telephone line for deenergizing said relay, whereby the said line switch is restored.

Signed by me at Chicago, Cook county, Illinois, this 28th day of March, 1906.

EDWARD A. MELLINGER.
